UNITED STATES PATENT OFFICE.

FREDERICK W. ROBERTSHAW, OF PITTSBURGH, PENNSYLVANIA.

WATER-HEATER.

1,097,265.

Specification of Letters Patent.

Patented May 19, 1914.

Application filed May 12, 1911. Serial No. 626,837.

To all whom it may concern:

Be it known that I, FREDERICK W. ROBERTSHAW, of Pittsburgh, Allegheny county, Pennsylvania, have invented a new and useful Improvement in Water-Heaters, of which the following is a full, clear, and exact description, reference being had to the accompanying drawings, forming part of this specification, in which—

10 Figure 1 is a side elevation, partly broken away, showing the preferred embodiment of my invention; Fig. 2 is a detail sectional view of the thermostatic valve and its connections, and the diaphragm valve and its 15 connections.

20 My invention has relation to water heaters, and more particularly to gas fired heaters having a heating element in which the water is heated and which is connected with a storage drum or reservoir.

25 My invention relates especially to improved valve mechanism for controlling the gas through the agency of a thermostatic device; and is designed to provide means of this character by which the gas is either fully turned on, or is entirely shut off (with the exception of a small pilot light) in a substantially instantaneous manner.

30 A further object of my invention is to provide means for taking care of any leakage of gas which may occur in a manner to prevent waste and interference with the proper operation of the burner.

35 The objects and advantages of my invention will more fully hereinafter appear.

In the drawings, the numeral 2 designates the casing of a heater having therein a heating coil 3 of any approved form, and which is connected at its lower end by a pipe 4 with the lower portion of a reservoir or drum 5. The upper end of the coil is connected by a pipe 6 to the upper portion of the drum or reservoir.

40 7 designates a gas supply pipe for supplying the burner 8 underneath the heating coil 3, and for also supplying the pilot light or burner 9.

45 10 is the casing of a diaphragm valve, which is interposed in the gas supply pipe 7 between the cut-off valve 7^a and the mixer 11 of the burner 8. The diaphragm casing 10 is formed in upper and lower sections suitably secured together, the lower section having a connection 12 for the inlet portion 50 of the pipe 7, and also a connection 13 for the outlet portion of the pipe 7 leading to

the burner. The two sections of the casing inclose the diaphragm chamber 14, into which the connection 12 leads, the opening into said chamber being surrounded by a 60 valve-seating flange 15.

16 designates a flexible diaphragm, which is secured at its edges between the two sections of the casing 10, and which divides the chamber 14 into two compartments. Attached to the under side of this diaphragm by means of a hollow screw 17 and clamping nuts 18, is a valve disk 19, which is arranged to seat upon the ring or flange 15. The screw 17 has a small aperture 20 in its 70 upper end. The upper section of the diaphragm casing has a central depending flange or cup 21, whose lower edge is a short distance above the diaphragm and against which the diaphragm is arranged to seat 75 when raised. This cup or flange is provided with a small perforation 22. The upper section of the diaphragm section is arranged with a connection 23 to receive a pipe 23^a leading to a thermostatically operated valve 24. The valve 24 may be of various forms, that illustrated being of the form substantially as shown and described in my Patent No. 998,262 dated July 18, 1911.

25 25 is a movable valve member, which controls the flow of gas and whose adjustable stem 26 is actuated by the thermostatic element 27. This thermostatic element is shown as extending upwardly into the lower portion of the drum or reservoir 5, the valve 90 casing being threaded into the lower end of said drum or reservoir.

28 is a pipe leading from the outlet side of the valve, and connected to the pilot light or burner 9 above its mixer 9^a. The pilot 95 light 9 is fed by a pipe 9^b leading from the lower portion of the diaphragm casing and having a regulating valve 9^c.

The operation is as follows:—The thermostatic valve 25 is provided with a spring 100 25^a which tends to hold the valve closed, this spring acting in opposition to the thermostat element 27, and being adjusted so as to be overcome by the action of said element when the desired temperature of water is 105 obtained in the drum or reservoir 5. When the burner 8 is in operation, the gas flows through the connection 12 into the lower compartment of the diaphragm chamber 14, and by its pressure on the under side of the 110 valve disk 19 lifts said disk sufficiently to permit the gas to pass between it and the

ring or flange 15 and thence to the burner. A small quantity of the gas will escape through the opening 20 of the hollow screw, and the diaphragm being pressed upwardly 5 against the lower edge of the coupler flange 22, this escaping gas will pass into the pipe 23^a and by the valve 25 into the pipe 28 and back in the pilot light or burner, where it is mixed with air and consumed. When the 10 water in the drum or reservoir 5 reaches the given temperature, the action of the thermostatic element 27 permits the spring 25^a to close the valve 25, so that the gas which has been escaping through the apertures 22 15 and 23 can no longer flow past the valve 25. When this takes place, the gas will accumulate in the upper compartment of the diaphragm chamber, until a pressure is created in such compartment sufficient to overcome 20 the pressure below the diaphragm, and to close the valve disk 19 against its seat 15. The flow of gas to the burner 8 is then immediately cut off and remains cut off until 25 the temperature of the water in the drum or reservoir 5 falls below the given temperature and causes the thermostatic element to again open the valve 25. The opening of the valve 25 relieves the accumulation of pressure in the upper compartment of the 30 diaphragm chamber, and enables the valve 19 to open and a full flow of gas again passed to the burner 8. The opening through the valve 19 is of a large area compared to the pipe area leading to the burner, 35 so that the action of said valve is practically instantaneous, and the gas at the burner will either be turned on in full, or closed off completely. The area of the valve opening 25 is also large compared to the area of the 40 escape openings 22 and 23, so that the action of this valve is also practically instantaneous.

An important feature of my invention consists in the fact that the valve mechanism 45 described operates to give either a full flow of gas at the burner 8, or entirely shuts off such flow. This is desirable for a number of reasons. In all heating systems where the heating is done in one member, and the 50 heated material is then passed to another member, the time required is sufficient to maintain, in an ordinary arranged boiler, hot water of different temperatures, running as much as thirty degrees in a boiler 55 five feet long and standing upright, as usually placed. The hot water is always drawn from the top of the boiler; and if the water at this portion of the boiler is at a temperature of say one hundred and forty degrees 60 and the thermostat which extends into the lower portion of the boiler is set to act at one hundred and ten degrees, the valve 25, as soon as it closes, shuts off the escapement flow of gas to the burner 9, and the flame 65 goes out at the burner 8. The draft, which

is very strong while the gas is burning, now drops to a very small amount, and the water circulation immediately ceases, and the water is dormant in the heater. The hotter water in the boiler, however, gradually 70 works down, and the colder water at the lower part where the thermostat is placed surely but slowly absorbs the heat in the hot portion, keeping the water above the thermostat slightly above its regulation, and 75 insuring a closed valve, until the temperature of practically all of the water in the boiler falls below one hundred and ten degrees. Unless the boiler and heater are in a very exposed place, if no water is drawn 80 from the boiler, the valve will remain closed for a number of hours. As there is no circulation from the heating element to the boiler and back, there is no chilling of the water by passing through the cold heater 85 as would occur did not the air currents or drafts substantially cease as soon as the gas ceases burning. Although the pilot light is still kept burning, the amount of gas consumed by it is very small, and even this 90 small amount is not wasted, as the greater part of the heat from it is absorbed by the heating member or coil. The heat waste is thereby reduced to a minimum, overheating is prevented, and the retarding circulation 95 feature above described is taken advantage of to the benefit of the device and to the accomplishment of one of the main purposes of the invention, namely, economic gas consumption. Furthermore, the practically instantane- 100 ous opening and closing of the gas supply port to the main burner, effectively prevents all danger of flashing back of the lighted gas in the mixer or Bunsen burner, which is extremely dangerous both to health 105 and to the surroundings. The present tendency in manufacturing is to increase the heating capacity of burners without increasing their size, and this is usually done by increasing the size of the holes in the burn- 110 ers. This makes the burners still more liable to flash, and the only safe remedy is to have the burner burn only at its greatest consuming point, doing its heating quickly, and then shut off quickly until such time as 115 the temperature is reduced, when the gas comes on again as quickly as it was shut off. This cutting off and turning on of the gas is effected by my invention too rapidly to permit flashing. 120

The returning of the escaping gas to the pilot light, not only prevents waste of fuel, but has a number of advantages over returning it into the main burner. In the first place, it insures the consumption of the 125 gas in case any leakage should occur by the valve 25 in its closed position. In the second place, if this gas should pass into the main burner, sufficient gas might be passed into such burner to cause flash-lighting in 130

the burner, which it is one of the objects of my invention to prevent. The amount of gas is so small that it can be readily taken care of in the pilot burner, and the main burner is always clean and ready to take care of the full flow of gas when the main valve opens, which occurs every time the thermostatic valve opens to exhaust the accumulated pressure in the upper compartment of the diaphragm chamber.

10 The provision of the escapement flange or cup 21, constitutes another important feature of my invention, since the escape opening 22 may be made so small as to prevent crowding of the pilot burner while the valve 25 is open. It also enables the opening 20 to be made much larger than would otherwise be possible; and since the accumulation of sufficient pressure above the 20 diaphragm is essential to the closing of the valve 19, it will be obvious that the larger this opening 20 is, the quicker this accumulation of pressure can be established. Without the provision of the escapement cup 21 25 and its escape opening, all the gas which passed through the opening 20 would, of course, pass through the valve 25 and back to the pilot light.

Owing to the fact that at each full opening of the diaphragm valve, the diaphragm is held tight against the periphery of the escapement cup, compelling the escapement to pass through the small orifice 22 (which, being of so small an area that the amount of 30 gas passing through it and to the pilot mixer, is hardly perceptible), the preponderance of pressure on the under side of the diaphragm is always maintained as long as the valve 25 is open. This insures the full 35 area for the pipeage of gas to the main burner 9. During the transition from open to closing, or vice versa, the larger amount of gas passing through the hole 20 is allowed to pass through the valve 25 to the pilot 40 light, thereby increasing its strength or flame at the critical moment, when the puff or otherwise explosion that is always present at the ignition or extinguishing of the flame in any form of gas burner occurs.

45 This is but momentary, and the larger amount of gas does not become wasted but is utilized to help as it were the diaphragm past its center. Instead of carrying the return connection for the escapement gas into 50 the mixer of the pilot light, it may be otherwise arranged to discharge its gas at a point where it will be consumed by said light. It will be noted that this return connection, as shown, discharges into the mixer of the 55 pilot light burner at a point above the openings therein for the admission of air. The discharge of gas from said pipe is therefore practically to the atmosphere. This is an important feature of my invention, since if 60 the discharge should be into the pilot light

supply pipe at a point where there is any gas pressure therein, a back pressure would be caused in the return or escape pipe connection which would interfere with the proper operation of the main valve. The escape pressure from the pressure-closing side of the diaphragm chamber is relatively low and a slight back pressure in the escape pipe is sufficient to effect the operation of the diaphragm and render it much less sensitive to 75 quick action.

70 It will be obvious that my invention is susceptible of many changes within the scope of the appended claims. Thus, it is applicable to heaters of various forms; the 80 details of the valves may be widely changed; and various forms of thermostatic elements may be employed, and other changes made.

75 While I have shown and described my invention as applied to a water heater, it will 85 be obvious that it is equally applicable to other forms of heaters and to the heating of a medium other than water.

What I claim is:—

1. In an automatic heating apparatus, the 90 combination of a pilot burner, having an air mixing chamber, a main burner, an automatic gas valve having a chamber provided with supply and discharge connections, a diaphragm in said chamber, a valve member 95 carried by said diaphragm and adapted to control the gas-supply to said main burner, such valve member being exposed to the gas supply pressure tending to unseat the same, said diaphragm being provided with a leakage port for building an opposing gas pressure at the opposite side of the diaphragm, an escape conduit leading from said opposite side of the diaphragm and discharging into said pilot burner at a point beyond the 100 air-mixing chamber, and thermostatic means 105 influenced by the heated medium and adapted to control the passage through said escape conduit, whereby said valve member is quickly opened and closed by gas pressure 110 in response to temperature changes in the heated medium; substantially as described.

2. In an automatic heating apparatus, the 115 combination of a pilot burner, having an air mixing chamber, a main burner, an automatic gas valve having a chamber provided with supply and discharge connections, a diaphragm in said chamber, a gravity-seated valve member carried by said diaphragm and adapted to control the gas-supply to 120 said main burner, said valve member being exposed to the gas supply pressure tending to unseat the same, said diaphragm being provided with a leakage port for building an opposing gas pressure at the opposite side of the diaphragm, an escape conduit leading from said opposite side of the diaphragm and discharging into said pilot burner at a point beyond the air-mixing 125 chamber, and thermostatic means influenced 130

by the heated medium and adapted to control the passage through said escape conduit, whereby said valve member is quickly opened and closed by gas-pressure in response to temperature changes in the heated medium; substantially as described.

3. In an automatic heating apparatus, the combination of a main burner, a pilot burner, an automatic gas valve having a 10 chamber provided with supply and discharge connections, a diaphragm in said chamber, a gravity-seated valve member on the diaphragm and adapted to control the gas supply to the main burner, said valve member being exposed to the gas supply pressure tending to unseat the same, a gas 15 passage communicating with the supply connection and with the portion of the chamber at the opposite side of the diaphragm, for 20 building an opposing gas pressure at the opposite side of the diaphragm, a gas escape passage leading from this portion of the chamber to the pilot burner beyond the air mixing chamber of said pilot burner, 25 and thermostatic means influenced by the heated medium and adapted to control the passage through said escape conduit, whereby said valve is quickly opened and closed by gas pressure in response to temperature 30 changes in the heated medium; substantially as described.

4. In an automatic heating apparatus, the combination of a main burner, a pilot burner, an automatic gas valve having a 35 chamber provided with supply and discharge connections for the main burner, a diaphragm in said chamber, a valve member on the diaphragm adapted to control the gas-supply to said main burner, said valve member being exposed to the gas supply 40 pressure tending to unseat the same, a leakage passage connecting the two portions of the said chamber at opposite sides of the diaphragm for building an opposing gas 45 pressure at the side of the diaphragm opposite the gas supply pressure, an escape conduit leading from said opposite side to the pilot burner, thermostatic means influenced by the heated medium and adapted 50 to control the passage through said escape conduit whereby said valve member is quickly opened and closed by gas pressures in response to temperature changes in the heated medium, and another constantly 55 open source of gas supply for the pilot burner and which is independent of the supply provided by said escape conduit; substantially as described.

5. In an automatic heating apparatus, the 60 combination of a main burner, a pilot burner, an automatic gas valve having a chamber provided with supply and discharge connections for the main burner, a

diaphragm in said chamber, a valve member on the diaphragm adapted to control the 65 gas supply to said main burner, said valve member being exposed to the gas supply pressure tending to unseat the same, said diaphragm having a leakage port for building an opposing gas-pressure at the opposite 70 side of the diaphragm, said chamber having at the last named side of the diaphragm a subsidiary chamber which is arranged to be closed by the diaphragm when the valve is in its full open position, and the subsidiary 75 chamber having a smaller leakage opening into the main chamber, a gas escape conduit leading to the pilot burner from said opposite side of the diaphragm, and means for controlling the passage through said escape 80 conduit to thereby control the opposing pressure on the diaphragm; substantially as described.

6. In an automatic heating apparatus, the combination of a main burner, a pilot 85 burner, an automatic gas valve having a chamber provided with supply and discharge connections for the main burner, a diaphragm in said chamber, a valve member on the diaphragm adapted to control the 90 gas supply to said main burner, said valve member being exposed to the gas supply pressure tending to unseat the same, said diaphragm having a leakage port for building an opposing gas pressure at the opposite 95 side of the diaphragm, said chamber having at the last named side of the diaphragm a gas escape conduit leading to the pilot burner, means for reducing the flow of gas through the leakage port when the said 100 valve is full-open, and means for controlling the passage through said escape conduit to thereby control the opposing pressure on the diaphragm; substantially as described.

7. In apparatus of the character described, having a main burner and a pilot burner, a valve for controlling the fuel supply to the main burner, a diaphragm chamber, a diaphragm for controlling the action of the said valve, the diaphragm having an escape opening leading to the opposite side thereof, and an escape connection leading from said opposite side of the diaphragm to the pilot burner and discharging to the latter at a point beyond that at which the normal gas supply for the pilot burner is mixed with air, whereby such discharge is free from back pressure, and means for controlling the said escape connection, substantially as described.

In testimony whereof, I have hereunto set my hand.
